UNITED STATES PATENT OFFICE.

HARVEY CONOVER, OF CHICAGO, ILLINOIS.

DOLL.

Application filed May 9, 1921. Serial No. 468,093.

To all whom it may concern:

Be it known that I, HARVEY CONOVER, a citizen of the United States, residing at Chicago, in the county of Cook and State 5 of Illinois, have invented a certain new and useful Improvement in Dolls, of which the following is a specification.

This invention relates to dolls for especial use in entertaining small children.

10 The object of the invention is to provide a doll of attractive form with an umbrella or other head decoration of sufficient size so that different faces may be concealed behind this head decoration and swung one by 15 one into view as the face of the doll, thereby changing materially the character of the doll and increasing the attractiveness and value of the doll just as though there were several dolls provided, but with only 20 one expense.

Another object of the invention is to provide such a doll with a moving face carrier which if moved with sufficient rapidity and with the necessary stop and start motion, 25 will serve the effect of changing the facial expression of the doll just as motion picture expressions change and thus add to the use of the doll in entertaining a child.

The invention consists in means for carrying 30 out the foregoing objects which can be easily and cheaply made, which is satisfactory in use and is not readily liable to get out of order. More particularly the invention consists in features and details of construction hereinafter more fully set forth in the specification and claim. Referring to 35 the drawings in which like numerals denote like parts,

Figure 1 is a face view of a doll mechanism illustrating this invention in its preferred form.

Figure 2 is a sectional detail view on the line 2-2, Figure 1.

In carrying out this invention a figure of 45 a doll 10, such as shown in the drawing, or any other desired form may be provided, the only essential point being that the body be surmounted by a large decorative member, in the particular case here illustrated 50 an umbrella top 12, provided with a handle 14 grasped by the hand 16.

The parts thus far described are made of cardboard or other convenient material, and there is provided at a proper point for the doll face, a perforation 18 thru which a suitably drawn, printed or painted face 20, carried on a disk 22 pivoted to the umbrella at 24, is visible. The essential feature of the device is that the decorative umbrella 12 be of sufficient area so as to completely conceal 55 the disk 22 and a plurality of faces of different expressions printed, painted or drawn on the face of the disk in suitable spaces 25-26-27-28-29.

The faces on the spaces 25-29 may be of 60 any artistic character conceived by the artist who draws them, but should preferably vary in given facial expression from laughter to tears and back again so that when the disk 22 is rotated to expose the successive 65 faces on the areas 25-29, dolls of different 70 expression will be produced from the original doll figure.

Attention is called to the fact that the 75 figure of the doll, viz., the dress outline, is cut away to make an attractive doll figure for decorative or children's play purposes and that this is rendered possible in combination with the changeable face feature by the fact that the face carrying disc is pivot- 80 ed above the doll's head, instead of below it, as in some prior devices.

Having thus described my invention, what I claim as new and desire to secure by Letters Patent is:

85 A cut out full length figure of a dressed and hatted doll having a face perforation and a disc pivoted above the doll's head to rotate behind the doll figure, carrying a plurality of faces adapted, as the disc is rotated, 90 to successively appear at said face perforation, for the purposes set forth.

In witness whereof I have hereunto subscribed my name in the presence of two witnesses.

HARVEY CONOVER.

Witnesses:

DWIGHT B. CHEEVER,
VELMA GRIFFITH.
